UNITED STATES PATENT OFFICE.

LAWRENCE N. MORSCHER, OF LAWRENCE, KANSAS, ASSIGNOR TO HIMSELF, AND
WILLIAM J. EHRSAM, OF ENTERPRISE, KANSAS, COTRUSTEES.

GRADER.

969,971.

Specification of Letters Patent. Patented Sept. 13, 1910.

Application filed October 19, 1908. Serial No. 458,558.

To all whom it may concern:

Be it known that I, LAWRENCE N. MORSCHER, a citizen of the United States, residing at Lawrence, in the county of Douglas and State of Kansas, have invented certain new and useful Improvements in Graders, of which the following is a specification.

The object of my invention is to produce an apparatus by means of which particles 10 may be separated into different grades by means of the effect of a deflecting fluid stream caused to enter transversely a flaring envelop of particles.

The accompanying drawing illustrates my 15 invention, Figure 1 being an axial section, diagrammatic in character but fully explanatory, no attempt whatever being made to even approximate proportions for the reason that exact proportions of any particular 20 machine would be dependent upon the particular material to be graded. Fig. 2 a detail of one of the tubes 18, adjacent tube 22 and associated parts.

In the drawings, 10 indicates a suitable 25 inclosing casing through the various parts of which fluid currents may be established. In the present structure the fluid current intended to be used is air, but it is to be understood that a different fluid current may be 30 used without departing from the spirit of my invention. Arranged within the casing 10 is a series of partitions 11, 12, 13, 14 and 41, which form chambers 15, 16, 17 and 42, having communication with the interior of 35 the main casing through valves 15', 16', 17' and 42' respectively. Mounted in partition 11 are a number of small cylindrical tubes 18, the receiving end of each of which communicates with the interior of the main casing 40 and the flared discharging end 19 gives access to the interior of chamber 15. Mounted within each tube 18 are deflecting means by which the particle-laden fluid current may be given a helical movement.

Leading to the receiving end of each tube 45 18 is a feed chute 21 through which a stream of particles to be graded may be delivered. Arranged in alinement with each tube 18 and mounted within partition 12, is a tube 50 22 having deflecting means 20 therein and having a discharge end 23. Similarly tubes 24 are mounted in partition 13 and said tubes are provided with deflectors 20 and a discharge end 25, and mounted in partition 55 14 are tubes 30 which aline with tubes 24.

Mounted in the final partition 41, in alinement with tubes 24, are tubes 26 which discharge into the main body of the casing 10. The several tubes may be of the same diameter, as shown in the upper part of the figure, or said tubes may be successively increased in diameter as shown in the lower part of the figure.

In order that strings, small sticks, etc., may not operate to clog the deflectors 20, I 65 find it convenient at times to provide the initial tube 18 with an auger-like deflector 31 having a pointed receiving end 32 and of less diameter than the interior of the tube so that particles, like strings, will, when engaged by the receiving end 32, be caused to pass to the exterior of the auger, pass freely 70 between it and the interior of the tube, and be thrown outward from the tube at its discharge end.

Any suitable means may be provided to produce fluid currents and a particle current of sufficiently high velocities and of a maintained ratio, but probably the most convenient means is an ordinary centrifugal 80 fan 35, the eye of which communicates with that part of the interior casing 10 into which tubes 26 discharge and the discharge chute 36 of which communicates with receiving ends of tubes 18 and passes the several valves 15', 16' and 17'.

The operation is as follows:—The fan being 90 set in motion, fluid currents are established through the several tubes and, by reason of the supply of air entering the receiving ends of tubes 18, and also by reason of the supply of air entering the other tubes from the particular compartments from which their receiving ends lead, the stream of particles passing down through a chute 95 21 will be delivered into one of the tubes 18 and there become mingled with the fluid current entering said tube and, by reason of the deflectors 20, will be given a helical movement which thus causes the particles 100 to assume the form of an envelop for the initial fluid current. When the particles reach the discharge end of tube 18 all of the particles of the envelop are projected in a flaring trajectory tending to carry said 105 particles out of the line of the tube and into compartment 15. The particular trajectories will depend upon the initial velocities both angular and translatory, and upon the conformation of the discharge end 110

of the tube. It is to be understood that the discharge ends of the tubes need not be flared, as shown in the drawings, but, on the contrary, they may be kept straight, or even choked, without departing from the spirit of my invention. The projected particles, as they leave the tube 18, are met by a fluid current which has entered through valve 15 and is passing into the receiving end of tube 22. The particles of differing masses issuing from the tube 18 will therefore be deflected to a greater or lesser extent and those which are deflected to the greatest extent will be carried back into alignment with tube 22 and pass, with the augmented fluid current, into said tube where the action already described is repeated. In the form shown in the upper part of the drawing, where the tubes are of uniform diameter, the translatory velocity increases because of the increase of volume of fluid current. The amount of this increase of velocity may be controlled, to a certain extent, by an adjustment of the controlling valves 15', 16' and 17'. The angular velocity, and to some extent the translatory velocity, may also be controlled by a variation of inclination of the deflecting vanes. In the form shown in the lower part of the figure the velocities may be determined by the increase in diameter of the tubes and, if desired, a variation of inclination of the vanes and a setting of the valves, in the manner already described.

I claim as my invention:

1. The combination, of a plurality of alined but axially separated tubes, means associated therewith for producing a helical movement of a particle-laden fluid-current through said tubes, means for delivering a multiplicity of particles to the first of said tubes, and means for establishing a deflecting fluid current between the separated adjacent ends of said tubes and from thence into and through the advance tube in opposition to the issuance of projected particles from the preceding tubes.

2. The combination, of a plurality of alined but axially separated tubes, deflectors arranged within for producing a helical movement of a particle-laden fluid-current through said tubes, means for delivering a multiplicity of particles to the first one of said tubes, and means for establishing a deflecting fluid current between the separated adjacent ends of said tubes and from thence

into and through the advance tube in opposition to the issuance of projected particles from the preceding tubes.

3. The combination of two alined tubes 60 the first having an outwardly flaring unobstructed discharge end adjacent but separated from the receiving end of the other tube, means for delivering a particle-laden fluid-stream to the receiving end of the first 65 tube and for establishing a helical movement of the said stream in said first tube, and means for introducing a deflecting fluid stream into the receiving end of said second tube. 70

4. The combination of two alined separated tubes, the first having an outwardly flaring delivery end delivering to the second, a helical deflector arranged in said first tube, means for delivering a particle-laden fluid-stream to the receiving end of the first tube, and means for introducing a deflecting fluid stream between the adjacent ends of the two tubes and from thence into and through the second tube. 75

5. The combination of two alined separated tubes, a delivery chute delivering to the receiving end of the first tube, means associated with the first tube for imparting a radial force to particles traversing said tube, 85 a collecting chamber surrounding the separated adjacent ends of the two tubes and having an air inlet, and a suction fan connected with the discharge end of the second tube, whereby the air current will enter the second tube between the adjacent ends of the two tubes and pass through said second tube toward the fan. 90

6. The combination of two alined separated tubes, the first having an outwardly 95 flaring delivery end delivering to the second, a helical deflector arranged in said first tube, a delivery chute delivering to the receiving end of the first tube, a collecting chamber surrounding the separated adjacent ends of the two tubes and having an air inlet, and a suction fan connected with the discharge end of the second tube. 100

In witness whereof, I have hereunto set my hand and seal at Indianapolis, Indiana, 105 this sixth day of October, A. D. one thousand nine hundred and eight.

LAWRENCE N. MORSCHER [L. N. M.]
